SINGLE ROTOR MIXER FOR PLASTIC MATERIAL

Carl F. Schnuck, New Haven, Conn., assignor to
 Farrel-Birmingham Company, Inc., Ansonia,
 Conn., a corporation of Connecticut

Application October 24, 1939, Serial No. 301,004

6 Claims. (Cl. 18—2)

This invention relates to a machine for mixing and kneading plastic material, and more particularly to a machine for mixing rubber, for example, and compounding it with various ingredients.

In processing rubber for commercial use the crude rubber is masticated or kneaded into a plastic mass and usually at the same time is mixed with various ingredients added to the mass of rubber, such as reinforcing pigments, softeners, fillers and vulcanizing agents. It is very essential that the mixing operation be complete so that a thorough dispersion of the various ingredients through the mass of rubber is obtained and a homogeneous product is secured. This is very essential to the uniformity of the product obtained by the mixing operation.

The present invention relates to a device for performing the mixing and kneading operations in a chamber of cylindrical shape, the chamber having an internally projecting rib at the intermediate portion thereof extending generally circumferentially of the chamber over a considerable portion of the circumference. There is provided within the chamber a single rotor having thereon a set of blades at each end, these blades being helically arranged so as to work the material toward the center of the chamber from each end thereof past the intermediate rib.

In the past, devices of this general character have been made for this purpose but in many of such devices it has been found that while the mixing action at the center of the chamber adjacent the rib over which the material is extruded or forced by the blades, is very thorough and efficient, the same is not true of the action adjacent the chamber ends, so that one part of the mass may be more thoroughly mixed than another and as a result it was difficult to secure a uniform, homogeneous product through which the various ingredients were thoroughly dispersed. In the present device this disadvantage has been overcome and a machine has been produced which not only brings about a thorough and effective mixing action so as to deliver a completely uniform product, but performs the mixing action in a relatively short time compared to the time required in the present machines, and also due to the arrangement and proportions of the device the mixing and kneading action may be carried on at a lower temperature than was previously the case.

These results are obtained in part by arranging a single cylindrical chamber, as already described, of such proportions that its diameter is at least

5 as great or greater than its length, so that the greater part of the action takes place adjacent the center of the chamber near the zone of the internally projecting rib. The diameter of the chamber being relatively large compared to its length also enables more effective cooling to be accomplished, as cooling passages may be provided substantially about the entire circumference of the chamber where the mixing action takes place.

10 One object of the present invention is the provision of a single rotor mixer for plastic material of improved and simple construction, which will bring about an effective and thorough mixing and mastication of the plastic material introduced into the chamber of the machine.

15 A further object of the invention is the provision of an improved mixing machine for plastic material having a chamber of cylindrical formation and a bladed rotor operating within the chamber, such that the greater part of the mixing and kneading action takes place adjacent the central part of the chamber as opposed to the end portions thereof.

20 25 A still further object of the invention is the provision of a device of the character described provided with a cylindrical chamber having an internally projecting extrusion rib on its inner surface at substantially the central portion of the chamber and a bladed rotor operating within the chamber, the blades being mounted in staggered relation upon each end of the rotor and extending helically to a point beyond the center thereof whereby the mass to be mixed will be rapidly moved toward the center of the chamber from the ends thereof and forced over the extrusion rib into the other side of the chamber to produce a thorough mixing and masticating of the charge of material.

30 35 40 To these and other ends the invention consists in the novel features and combination of parts to be hereinafter described and claimed.

In the accompanying drawings:

45 Fig. 1 is a front elevational view of a single rotor mixer embodying my invention, with the chamber and rotor being shown in section;

Fig. 2 is a transverse sectional view on line 2—2 of Fig. 1;

Fig. 3 is a development view of the surface of 50 the rotor as it would appear if flattened out;

Fig. 4 is an end elevation of the rotor, and

55 Figs. 5, 6 and 7 are front elevational views of the rotor showing it in progressive positions during its rotation.

To illustrate a preferred embodiment of my

invention I have shown a mixer comprising a base 10, having end standards 11 and 12 rising therefrom, which standards are provided with bearings 13 and 14 to rotatably support a rotor shaft 15 upon which is secured a driving gear 16, driven by a pinion 17, which may in turn be actuated from any suitable source of power (not shown).

Supported from the standards 11 and 12 are end members 18 and 19 of annular formation, so that the rotor may pass through the central opening therein. Supported between these two plates is the chamber body 20 of cylindrical formation, this body being cored out to provide passages 21 for a cooling fluid so that the temperature may be regulated during the operation of the device. It will, of course, be obvious that if it is desired to carry out a mixing operation under a high temperature a heating medium instead of a cooling medium may be introduced into the passages 21.

Arranged circumferentially of the chamber body 20 at substantially the central portion thereof is an inwardly projecting rib 22, shown in transverse section in Fig. 1. The chamber is provided with an upper charging opening 23 and a lower discharge opening 24, and from reference to Fig. 2 it will be seen that the inwardly projecting rib 22 extends circumferentially about the inner surface of the chamber from one of these openings to the other. These openings, as shown in Fig. 2, are located at one side of the vertical center line of the chamber so that the rib extends about a considerable portion of the circumference. It will also be noted that the rib is relatively shallow as compared with the diameter of the chamber, and projects inwardly toward the axis of the chamber a relatively short distance.

The chamber may be charged through the hopper 25 which leads into the charging opening 23 and this opening may be closed by a plunger 26 during the operation of the machine. Likewise, the discharge opening 24 is closed by a door member 27 secured to a sliding cylinder 28, which cylinder is slidably mounted on supports 29 and 30 carried by the base so that the door may be slidably moved toward the left, as shown in Fig. 1, to permit the material to be discharged through the opening 24 after the mixing operation is completed.

Secured to the rotor shaft 15 is a winged or bladed rotor 31, the body of which may be cored out to provide hollow interior passages 32 for the reception of a temperature-controlling fluid introduced through the shaft openings 33.

Upon each end of the rotor are a number of blades which project from the body thereof toward the inner periphery of the chamber. As shown in Fig. 3, three of these blades 34 are provided upon each end of the rotor, making six in all, although this number may be varied as desired. The blades at one end of the rotor are arranged in staggered relation with respect to those of the other end, and it will be noted that the blades are arranged helically on the surface of the rotor with the leading edge adjacent the ends of the rotor so that during the rotation of the latter in the direction of the arrows in Figs. 1, 2 and 4, the charge of material within the chamber will be moved from the end portions toward the center thereof past the rib 22 and forced over into the other end of the chamber between the wall thereof and the surface of the rotor in that end.

It will also be noted that as shown in Figs. 3

and 5 to 7, the blades of the rotor extend to some extent beyond the center line thereof or beyond the intermediate extrusion rib 22, but are of less height adjacent their inner ends as will be hereinafter explained, so as to leave some clearance opposite the rib through which the material may pass over into the other end of the chamber to be caught, and operated upon, by the blades in that end.

Supported by the end members 18 and 19 are a pair of annular plates 36 and 37 which form the end members of the chamber. Just below these members are mounted rings 38 and 39, held in place by the supports 40 and 41, which rings fit closely the openings within the plates 36 and 37. Secured in the end faces of the rotor are annular members or rings 42 and 43, which bear tightly against the rings 38 and 39 so as to close the chamber ends about the rotor effectively and prevent any of the ingredients from being forced out of the chamber at this point.

It will be noted that the ends of the rotor fit closely against the plates 36 and 37 so as to obviate as far as possible, the entrance of any of the material between the end of the rotor and these plates. Also, it will be noted from Figs. 3 and 5 to 7 that the blades 34 are arranged at a relatively large angle with respect to the rotor axis so that as these blades attack the material the tendency will be to drive it toward the central portion of the chamber instead of around the periphery thereof, thus moving the material sharply away from the ends of the chamber toward the intermediate rib and past this rib into the other end of the chamber.

In Figs. 5, 6 and 7 of the drawings, the progressive action of the rotor and blades thereon is shown. For example, in Fig. 5 one of the blades 34 has arrived at the point where its outer edge A is at the highest point of the circumference of the chamber, and it will be noted that the tip of the blade at this point works close to the inner periphery of the chamber wall. This is true of the tip of the blade along its entire length until the intermediate extrusion rib is reached. In Fig. 6 of the drawings, the rotor has progressed through a small angle of its rotation until the central portion B of the blade 34 has reached the highest point of the chamber, and it will be noted that the clearance of this portion of the blade is substantially the same as shown between the point A thereof and the chamber wall in Fig. 5. As shown in Fig. 7 of the drawings, a further rotation of the rotor has taken place until the inner end C of the blade tip has arrived at the upper portion of the chamber. It will be noted that the point C is substantially opposite the beginning of the extrusion rib 22, and that there is substantially the same clearance between the point C and the chamber wall as between the latter and the points A and B. It will also be noted from Fig. 7 that the blade 34 falls away rather sharply from the point C, as shown at D, and while this blade extends beyond the rib 22 there is considerable clearance between this rib and the surface D of the blade, so that the material may be forced or extruded through the opening between the blade and the extrusion rib into the right-hand end of the chamber, as shown in these figures.

The blades of the rotor are of substantially the same formation and the action described with respect to one will be repeated each time the charge is encountered and picked up by one of the blades. It will be apparent that, due to the

relatively great helical angle of the blade with respect to the rotor axis (about 60° as shown), the material will be moved sharply from the end of the chamber toward the center thereof and extruded or squeezed under considerable pressure past the extrusion rib into the other side of the chamber, where it will be picked up by the next succeeding blade in that end of the chamber and the action repeated. The charge will thereafter be kept principally at the central part of the chamber to be moved back and forth past the extrusion rib where the most intense and thorough mixing and masticating action takes place, resulting in a thorough dispersion of the ingredients through the mass, so that a homogeneous and plastic product will be delivered from the machine. Moreover, the mixing will be accomplished by a minimum amount of travel of the charge circumferentially of the chamber, as the tendency of the rotor blades is to work the material back and forth instead of moving it circumferentially, although there will, of course, be a certain amount of the latter movement.

As the diameter of the chamber is relatively great as compared to its length (the ratio being about 1½ to 1, as shown), the greatest portion of the working surface is provided adjacent the center of the chamber where the most effective action takes place. Thus during a single rotation of the rotor, each blade will work over an area of the chamber having a small axial dimension and a relatively great circumferential dimension, so that the action of each blade is over an area close to the rib at the central portion of the chamber. The provision of a plurality of such blades and their relatively large angle with respect to the rotor axis results in the charge being continually crowded to, and past, the central rib, so that the charge is confined to a constricted area on either side of this rib.

As will be apparent from Figs. 4, and 5 to 7, the rotor blades are rounded or convex upon both their leading and trailing faces, and that these faces are of similar shape, so that no pockets or eddies will exist at the rear or trailing faces of the blades in which portions of the charge might tend to lie dormant. As will be seen, particularly from Fig. 4, the angle at the tip of the blades between the front and rear faces thereof is approximately 60°, the end face of the rotor presenting a configuration roughly approximating an equilateral triangle. At their inner ends the blades are gently rounded from the highest point of the blade tip toward the body of the rotor, which rounded portion lies substantially in the plane of the rib 22. This rounded portion of the blade where it faces the rib surface expedites movement of the material of the charge over the rib and prevents any catching or trapping of the material in pockets or the like during the operation of the mixer. This shape of the inner end portions of the blade, together with the fact that these portions of the blades extend slightly beyond the center line of the rotor, result in the working face of the rotor presenting a tortuous depression or valley skirting the inner ends of the blades, as indicated on Figs. 5 to 7, and it is through this depression that the material is forced during the operation of the device.

While I have shown and described a preferred embodiment of my invention, it will be understood that it is not to be limited to all of the details shown, but is capable of modification and

variation within the spirit of the invention and within the scope of the appended claims.

What I claim is:

1. In a machine for mixing plastic substances, a cylindrical mixing chamber provided with a constricted central portion, the diameter of said chamber being greater than the length thereof, a cored rotor of relatively large diameter in said chamber having a plurality of blades upon each end for moving the material back and forth past said constricted portion and also circumferentially of the chamber, said blades being helically arranged at an angle of substantially 60° to the rotor axis to move the material sharply toward the center of the chamber from the ends thereof, and the ratio of the diameter of said chamber to the length thereof being substantially 1½ to 1.
2. In a machine for mixing plastic substances, means providing a cylindrical mixing chamber having an inwardly projecting rib adjacent its central portion, said chamber being relatively short with respect to the diameter thereof, a rotor in said chamber having upon each end thereof a plurality of helically arranged blades to work the material back and forth past said rib, and said blades making a sharp angle with the rotor axis, said chamber having a charging opening at the top and a discharge opening at the bottom, said openings lying at one side of the rotor axis, and said rib extending from one opening to the other whereby it extends over a major portion of the circumferential dimension of the chamber and said blades having convex front and rear surfaces.
3. A rubber mixing machine of the enclosed type comprising a substantially cylindrical casing providing a mixing chamber, the diameter of which is greater than the length thereof, said chamber having a constricted portion therein intermediate of its ends, the constriction being in the form of a rib having gradually sloping sides, and a rotor of relatively large diameter in said chamber for working the material alternately in opposite directions over said rib and circumferentially of the chamber whereby the entire charge is moved in a tortuous path, said rotor having within each end of the chamber a plurality of blades the surfaces of which facing the surface of the chamber are rounded, said blades having a sharp pitch, and the inner end portions of said blades being located adjacent said rib but with substantial clearance in respect thereto and rounded to facilitate movement of the material over and past the rib, and said blades being helically arranged and making an angle of substantially 60° with the rotor axis.
4. A rubber mixing machine of the enclosed type comprising a casing of substantially cylindrical form providing a mixing chamber, a gradually sloping rib projecting into said chamber at its middle portion and constricting the diameter thereof, and a rotor for working the material around the chamber in a tortuous path and back and forth in said chamber over and past said rib, said rotor having blades in each end of the chamber, the inner ends of said blades being located adjacent said rib and having substantial clearance with respect thereto, said blades each being symmetrically formed so that its rear conformation is similar to its front conformation, there being three blades in each end of the chamber, and the front or working face of each blade forming an angle of approximately 60° with respect to the rear face thereof.
5. A rubber mixing machine of the enclosed

type comprising a casing of substantially cylindrical form providing a mixing chamber, a gradually sloping rib projecting into said chamber at the middle portion thereof and constricting its diameter, and a rotor having a plurality of closely set, sharply pitched, but generally rounded blades in each end of the chamber to work the material over and past said rib, said blades having their inner ends adjacent the rib but provided with substantial clearance with respect thereto, said rotor having in its face in the region adjacent the rib a tortuous rotor-encircling valley or depression skirting the inner ends of said blades, and said blades making an angle of substantially 60° with the rotor axis to work the material in the tortuous path of said valley.

6. A rubber mixing machine of the enclosed

type comprising a substantially cylindrical casing providing a mixing chamber, a gradually sloping rib extending into the chamber midway of its length, and a rotor for working the material in a tortuous path around the chamber and back and forth over the surface of said rib, said rotor having three blades in each end of the chamber in staggered relation to the blades in the opposite end, said blades making an angle of substantially 60° with the rotor axis and each having rounded convex front and rear surfaces arranged at an angle of approximately 60° to each other and having inner end portions facing the surface of the rib which are rounded in order to facilitate passage of the material over the rib.

CARL F. SCHNUCK.
